UNITED STATES PATENT OFFICE.

JOHN W. OSBORNE, OF ALSEY, AND CHARLES C. FREITAG, WINCHESTER, ILLINOIS.

WIRE STRETCHER.

Application filed January 31, 1927. Serial No. 165,007.

This invention relates to the class of pushing and pulling implements and pertains particularly to a wire stretching device.

The primary object of this invention is to provide, in a manner as hereinafter set forth, a wire stretcher having an improved wire gripping means, easily and quickly engaged or disengaged and designed to exert its gripping engagement on the wire in proportion to the pressure or force applied to the tool for the stretching of the wire.

Another object of the invention is to provide a wire stretcher of the character described which will be easy to handle and operate, efficient, and comparatively inexpensive to manufacture.

Numerous other objects of the invention will become apparent as the description of the same proceeds, and the invention will be best understood from a consideration of the following detailed description taken in connection with the accompanying drawings forming a part of this specification, with the understanding, however, that the invention is not confined to any strict conformity with the showing of the drawings, but may be changed or modified so long as such changes or modifications mark no material departure from the salient features of the invention, as expressed in the appended claims.

In the drawings:

Figure 1 is a top plan view of the tool embodying this invention, shown as in use.

Figure 2 shows the tool partly in vertical longitudinal section.

Figure 3 is a transverse section taken substantially upon the line 3—3 of Figure 1.

Referring now to the drawings in detail wherein like numerals of reference indicate corresponding parts throughout the several views, numeral 1 indicates a relatively broad, flat elongated body, which may be constructed of wood or a light but strong metal and at the outer end of the body a handle 2 is formed by cutting inwardly upon each side of the body to form the reduced extension shown. At the other or inner end of the body one broad face thereof is provided with the enlargement 3 which is formed of the same width as the body and which has the inner edge wall formed substantially semi-circular as indicated at 4, this wall being convex as shown. The central portion of the wall 4 is provided with the gripping teeth 5. Pivoted to the central portion of that face of the tool body 1 upon which the enlarge-

ment 3 is formed, is a gripping dog 6, pivotally held upon the body by the pin 7 and having the curved eccentric face 8 formed to set up gripping teeth 9 which work in opposition to the teeth 5 when the dog is swung about its pivot.

An actuating arm 10 extends from one side of the dog to and beyond one side edge of the body 1 and has an eye 11 formed therein for the reception of one end of a link 12.

Surrounding the body 1 adjacent the outer end thereof is a broad band 13 which is provided with a central slot 14 extending longitudinally of the body, through which a retaining pin 15, carried by and extending from one face of the tool body, projects. One side of the band 13 has an apertured ear 16 formed thereon and projecting laterally therefrom through the aperture of which ear the other end of the link 12 engages.

Projecting from a central portion of the inner end of the body is formed a post engaging spur 17, which is adapted to be forced into a tree or post to form a fulcrum for the body to swing from.

Reference to Figures 1 and 2 of the drawings will readily show the operation of this device, for it will be seen that the spur 17 is adapted to engage a tree or post 18 with that face of the body carrying the enlargement 3 and dog 6, uppermost.

With the tool in this position, the band 13 is slid inwardly upon the body causing the dog 6 to be swung to widen the space between its eccentric toothed face and the toothed face of the curved portion 4 of the enlargement.

The wire 19 which runs from another post is then placed between the two toothed surfaces and by pulling the sleeve 13 outwardly it will be readily seen that the dog will be caused to bind the wire between the surfaces described. By pulling upon the handle 2, as for example, to the right, the grip of the dog 6 upon the wire 19 will be increased while the wire is being over an adjacent post.

From the foregoing description it will be readily observed that the structure described is of simple construction and will be easy to operate.

Having thus described our invention, what we claim is:

1. A wire stretcher of the character described, comprising an elongated body member, a spur upon one end of the body for securing the same to a fixed element, a fixed jaw upon one face of said body adjacent the

spur carrying end and curving across the face thereof, a pivotally mounted jaw upon the same face of the body as said fixed jaw and having one face arranged in opposed relation 5 to the working face of the fixed jaw, the working face of said pivoted jaw being eccentrically curved to increase or decrease the space between the jaws when the pivoted jaw is swung about its center, a control arm carried by the pivoted jaw and extending beyond one side of the body member, a band surrounding and slidably secured to the body member adjacent the outer end thereof, and a link connection between said band and the 10 outer end of said arm, for swinging the jaw upon shifting the band longitudinally of the body member.

2. In a wire stretcher of the character described, comprising an elongated member, a 15 spur extending longitudinally of and from one end of the member for securing the

same to a fixed object, a fixed jaw upon the member adjacent the spur carrying end thereof, said jaw having the working face thereof of arcuate contour, a pivoted jaw member secured to the elongated member adjacent the working face of the fixed jaw and having an eccentric working face co-acting with the fixed jaw, an arm carried by said pivoted jaw extending laterally of the elongated member and toward the rear of the same, a relatively broad band surrounding the elongated member adjacent the rear end thereof, and adapted for limited movement longitudinally thereon, a laterally extending ear carried by said band, and a link member connecting said ear with the free outer end of said jaw arm.

In testimony whereof we affix our signatures.

JOHN W. OSBORNE.
CHARLES C. FREITAG.
